UNITED STATES PATENT OFFICE

165,892

DINNER PLATE OR SIMILAR ARTICLE

Nettie Zimmerman, Los Angeles, Calif.

Application November 6, 1950, Serial No. 12,855

Term of patent 7 years

(Cl. D44—15)

To all whom it may concern:

Be it known that I, Nettie Zimmerman, a citizen of the United States, residing at Los Angeles, in the county of Los Angeles, and State of California, have invented a new, original, and ornamental Design for a Dinner Plate or Similar Article, of which the following is a specification, reference being had to the accompanying drawing, forming part thereof.

Figure 1 is a top plan view of a dinner plate or similar article showing my new design, and

I claim:

The ornamental design for a dinner plate or similar article, as shown.

NETTIE ZIMMERMAN.
